VALVE

Charles S. Crickmer and Hans C. Glitsch, Dallas,
Tex., assignors to Merla Tool Company, Dallas,
Tex., a firm

Application October 30, 1936, Serial No. 103,316

9 Claims. (CL. 166—2)

This invention relates to new and useful improvements in valves.

One object of the invention is to provide an improved valve adapted to be connected in a well tubing for emptying or unloading the liquid from the annular space between the tubing and well casing.

An important object of the invention is to provide an improved valve for controlling a flow of fluid from the interior of the well casing to the interior of the well tubing, and being constructed so as to be operated by the fluid, whereby said valve is opened when fluid to be drained is present in the casing and closed when no fluid is within said casing.

Another object of the invention is to provide an improved valve arranged to be connected in a well tubing above the usual well packer, and including a chamber adapted to be acted upon by the fluid in the casing outside the tubing to actuate a valve which controls the flow from said casing to the tubing, whereby the use of a float, with its incidental disadvantages, as well as the necessity of providing perforations in the tubing for permitting such flow, are eliminated.

A further object of the invention is to provide an improved valve for controlling the flow of fluid from a well casing to a well tubing, which is automatically operated by the presence of fluid in the casing and which is not affected by well pressures, or subject to deterioration by contact with the well fluid.

Still another object of the invention is to provide an improved valve including a solid operating member, the structure being such that when said member is submerged in fluid, the resultant decrease in weight of said member is utilized to operate the valve.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in section and partly in elevation of a valve, constructed in accordance with the invention.

Figure 2 is an enlarged view, partly in section and partly in elevation of the valve member and seat.

Figure 3 is an enlarged horizontal, cross-sectional view, taken on the line 3—3 of Figure 1.

Figure 4 is a view, partly in section and partly

in elevation, of a modified form of the invention, Figure 5 is a horizontal, cross-sectional view, taken on the line 5—5 of Figure 4, and

Figure 6 is a horizontal, cross-sectional view, taken on the line 6—6 of Figure 4.

In the drawings, the numeral 10 designates an elongate, cylindrical shell or housing having an upwardly extending reduced collar 11 preferably made integral with its upper end. The lower end of the shell or housing is open, as is clearly shown in Figure 1. The upper end of the bore of the collar 11 is provided with screw threads 12, whereby the well tubing 13 may be secured into the upper end of said collar. The lower end of the bore of said collar is also threaded, as shown at 14, and this threaded portion receives the upper end of an elongate tubular mandrel 15. The mandrel has a greater length than the length of the shell or housing 10 and as is clearly shown in Figure 1, said mandrel extends axially through said shell and has its lower end depending from the open end of the shell. The extreme lower end of the mandrel is externally threaded at 16 whereby this lower end may be connected to the well tubing (not shown). With this arrangement, it is obvious that the shell and mandrel carried thereby, may be connected in a string of well tubing, whereby they may be lowered with the tubing string into the well casing A. It is noted that the outer diameter of the shell or housing is substantially the same as the inner diameter of the well casing A, whereby there is only a slight clearance between the shell and casing.

For guiding the shell and mandrel downwardly within the casing A when the same is attached in the tubing string, a plurality of radially extending guide members 17 are provided at the lower end of the mandrel 15 just above the screw threads 16. As clearly shown in Figures 2 and 3, each guide member has its inner surface engaging the face or outer surface of the mandrel and is welded, or otherwise suitably fastened to said mandrel. The extreme upper end of each guide member abuts an annular flange 18 which is formed on the mandrel, the flange being located within the lower end of the shell or housing 10. The upper end of each guide member also engages within the lower open end of the shell and, if desired, may be secured to said shell. The outer face of each guide member is substantially in vertical alignment with the exterior surface of the shell and as the device is lowered into the well casing but also act as spacers between the shell of each guide member 17 will ride on the inner

surface of said well casing, whereby the shell and mandrel are guided axially within said casing. It is pointed out that the guide members not only serve to guide the device axially within the well casing but also act as spacers between the shell 10 and the mandrel 15, whereby the mandrel 15 is held in axial alignment within the shell.

Above the annular flange 18 on the mandrel 15, which flange is engaged by the upper end 10 of each guide member, the mandrel is formed with a second flange 19 which is spaced some distance above the flange 18. This flange is also preferably made integral with the mandrel but does not extend outwardly from said mandrel 15 the same distance as does the lower flange 18. Between the flanges 18 and 19, a plurality of openings or ports 20 are provided, whereby fluid from the well casing may enter the open lower end of the shell and flow into the ports 20 and 25 then into the interior of the mandrel 15, from which point said fluid may pass upwardly into the well tubing 13. Thus, it will be seen that the ports or openings 20 establish a communication between the interior of the well casing A and the 25 interior of the well tubing 13.

For controlling the flow of fluid through the openings 20, a valve member or sleeve 21 surrounds the mandrel 15 adjacent said ports. The internal diameter of the valve sleeve 21 is substantially the same as the external diameter of the upper flange 19, whereby said sleeve is slideable vertically over this flange. The extreme lower end of the sleeve is provided with an internal bevel 22 which is arranged to seat on a 35 complementary bevel 22' which is formed on the upper end of the lower flange 18 (Figure 2). Near its upper end the sleeve is provided with an internal shoulder 23 which is so located within the sleeve that when the bevel 22 is engaging the 40 seat 22', this shoulder 23 is engaging the upper end of the flange 19. Thus, it will be seen that when the bevel 22 at the lower end of the sleeve and the shoulder 23 near its upper end are seated, fluid cannot pass from the interior of the casing 45 A and shell 10 through the ports into the interior of the mandrel. However, when the sleeve 21 is raised to the position shown in full lines in Figure 1 and dotted lines in Figure 2, then the ports 20 are uncovered and fluid from the well casing may enter the mandrel 15. Therefore, 50 it will be seen that the sleeve 21 positively controls the flow of fluid from the well casing A to the well tubing 13.

For actuating the valve sleeve 21 to cover and uncover the openings 20, an elongate annular casing 24 surrounds the mandrel 15, being located in the annular space formed between the mandrel 15 and the shell or housing 10. The lower end of the casing 24 is closed while the 55 upper end thereof is open. It will be seen that the casing forms an annular vertical chamber which is open at its upper end. The lower end of the chamber is provided with an annular depending skirt 25 which is preferably made integral therewith. The skirt or apron is spaced from the outer surface of the mandrel 15 (Figure 2) whereby an annular space 26 is formed between the mandrel and said skirt. The extreme lower 60 end of the skirt is externally screw threaded so that the upper end of the valve sleeve 21 may be screwed thereon. With this arrangement, it will be obvious that the valve sleeve 21 which controls the flow through the openings or ports 20 is carried by the annular vertical casing 24.

75 As is clearly shown in Figure 1, the casing 24

may undergo a vertical movement within the shell 10, and this casing is normally held in its upper or raised position by a coiled spring 27 which is located in the annular space 26, being confined between the upper flange 19 on the mandrel 15 and the underside of the casing 24. When said casing is in its raised position the upper end thereof abuts a depending ring 11' which is formed within the upper end of the shell 10. It is, of course, obvious that when the casing is raised, the valve sleeve 21 is also raised so that it is not in engagement with the bevelled seat 22' on the flange 18 and therefore, at this time, fluid may flow from the well casing A into the mandrel 15 and then into the tubing 13. A plurality of 10 relief ports 28 are formed in the upper end of the shell or housing 10 at a point just below the upwardly extending collar 11, as is clearly shown in Figure 1.

In operation, the device is connected in the 20 tubing string, as has been explained and is ordinarily located just above the well packer (not shown) which is also carried by the tubing. During the lowering operation, the coil spring 27 is, of course, holding the annular casing 24 in a raised 25 position, which holds the sleeve valve 21 in its raised position whereby the ports 20 are uncovered. As the device enters the fluid standing within the well casing A, it will be obvious that such well fluid will flow into the shell 10 and will submerge 30 the entire device. The fluid will, of course, enter the open top of the annular casing 24. Assuming that the packer (not shown) is set at a point where the entire device is submerged in well fluid, it will be seen that the fluid being 35 within the annular casing 24 as well as outside of the same, there will be an equalization of fluid pressure within and without said casing and, therefore, the coil spring 27 which is sufficient to support said casing will hold the same in 40 its raised position.

The casing 24 will remain in this raised position until such time as the fluid within the casing A has passed through the openings or ports 20 into the mandrel 15 and finally into the tubing 13. So long as the casing 24 remains submerged in the well fluid there will be no change in its position and, thus, there will be no change in the position of the sleeve valve 21 which will remain open during this time. As soon as the well fluid within the casing A has drained through 45 the ports 20 into the mandrel and tubing 13 to a point where the fluid level within the well casing A has dropped some distance below the top of the annular casing 24, then it will be 50 seen that the weight of the fluid within the casing 24 is added to said casing. This additional weight of the fluid within the casing 24 overcomes the tension of the coil spring 27 so that the casing 24 is lowered by gravity, which 55 action lowers the sleeve valve 21 so that the bevel 22 at its lower end engages the bevelled upper end 22' of the lower flange 18, and the internal shoulder 23 of said sleeve valve 21 engages the 60 upper end of the annular flange 19, whereby the ports or openings 20 are closed. Thus, the flow of well fluid from the well casing A into the mandrel 15 is stopped.

The sleeve valve will remain in its lowered or closed position until such time as the well fluid 70 within the well casing A rises to a point above the top of the open annular casing 24. When the fluid level rises above said casing, then it will be obvious that such casing is again submerged in the fluid. As soon as this occurs, the 75

fluid pressure within and without the casing is the same and the only weight which is placed upon the coil spring 27 is the actual weight of the casing 24 because the volume of fluid displaced by the casing is substantially equal to the volume of fluid trapped within said casing. Therefore, upon submerging the casing, the weight of the casing and trapped fluid is lightened to permit the spring to raise the casing. This 10 coil spring will immediately raise the casing to its uppermost position which will cause the sleeve valve 21 to be slid upwardly, whereby the ports or openings 20 are again uncovered. Uncovering of these openings will, of course, permit the 15 fluid standing within the well casing A to flow into the mandrel 15 and tubing 13, whereby drainage of this fluid standing in the well casing is accomplished. Of course, as soon as sufficient of the fluid drains into the tubing to lower 20 the level below the top of the casing 24, then said casing will again be lowered, as has been explained, to again close the valve 21 and thereby cover the ports.

It will be obvious that the action is entirely 25 automatic being controlled by the fluid itself. That is, when the fluid level is high enough to submerge the casing 24, then the coil spring 27 raises said casing to open the ports or openings 20. Whenever the fluid level outside the casing 30 falls below a predetermined level, the weight of the fluid within the casing will cause the same to overcome the spring tension and thus close the ports.

It is noted that no float is employed in operating the valve. It has been found that a float is 35 most impractical because if a hollow float is made light enough to operate the valve it is not strong enough to withstand the heavy pressures always found in wells and, therefore, the float would be crushed. If such float were made strong enough to stand the pressure it is too heavy to float. Some experimental work has been done in using solid non-metallic floats but their failures are due to the fact that so far no material has been 40 found which can remain submerged in an oil well for a long period of time without becoming soaked or water-logged and losing its buoyancy with the result that its efficiency fails. The structure shown and described herein eliminates 45 the pressure difficulty as the pressure on the inside of the chamber is equal to and balances the pressure on the outside of the chamber. The weight of the fluid trapepd within the casing 24 is depended upon to lower the chamber and thus 50 close the valve. A positive automatic action is had at all times and since there are few working parts to the invention, it has been found that 55 it may remain in a well for a great length of time and operate efficiently under all conditions.

In Figures 4 to 6, we have shown a modified 60 form of the invention, wherein an annular solid body 30 is substituted for the annular casing 24. This body is preferably constructed of metal and has a depending skirt 25', to which the upper end 65 of the valve sleeve 21 is secured. The coil spring 27 is confined within the skirt 25' and exerts its pressure against the lower end of the body 30. The weight of the body is such that normally, 70 the spring is compressed and the valve sleeve 21 is in its lowered position, closing the ports 20.

The operation of this form is obvious. When 75 the assembly is first lowered into the well casing, the valve sleeve is in its lowered position, which closes the ports. As soon as the annular body 30 is submerged in the well fluid, the weight

of said body is decreased with relation to the volume of fluid it displaces. This decreases in weight due to submersion, permits the coiled spring 27 to immediately raise the body 30, which raises the valve sleeve to uncover the ports 20. 5 The fluid in the casing escapes into the tubing, as has been described, and when the body 30 is no longer submerged in fluid, the weight of said body compresses the spring to slide the valve sleeve downwardly to close the ports 20. Obviously, when sufficient fluid enters the casing to again submerge the body 30, the ports are again opened.

What we claim and desire to secure by Letters Patent is:

1. A valve including, a tubular mandrel adapted to be connected in a tubing string and having openings therein whereby communication between the well casing and mandrel is established, means for controlling the flow from the casing 20 to the mandrel, a non-buoyant movable casing connected to the control means and having a hollow portion at its upper end, said hollow portion having an open top whereby well fluid from the well casing may enter the same, and means 25 for supporting the non-buoyant movable casing to hold the control means open so long as the non-buoyant movable casing is submerged, the lowering of the fluid level below the top of said casing causing fluid to be trapped in the casing 30 and the weight of this fluid overcoming the supporting means to close the control means and cut off the flow, whereby the level of the fluid controls the operation of the control means.

2. A valve including, a tubular mandrel adapted to be connected in a tubing string and having openings therein whereby communication between the well casing and mandrel is established, means for controlling the flow from the casing to the mandrel, and a non-buoyant movable casing connected to the control means for actuating the same and subjected to the well fluid within the well casing, the non-buoyant movable casing having a hollow portion at its upper end, said hollow portion having an open top whereby the well fluid may enter the same, whereby the position of the casing and control means connected thereto is dependent on whether or not the non-buoyant movable casing is submerged in the well fluid.

3. A valve including, a tubular mandrel adapted to be connected in a tubing string and having openings therein whereby communication between the well casing and mandrel is established, means for controlling the flow from the casing to the mandrel, a movable casing connected to the control means and having a hollow portion at its upper end, said hollow portion having an open top whereby well fluid from the well casing may enter the same, and a resilient means for supporting the movable casing to hold the control means open so long as the movable casing is submerged, the lowering of the fluid level below the top of said casing causing fluid to be trapped in the casing and the weight of this fluid overcoming the tension of the supporting means to close the control means and cut off the flow, whereby the level of the fluid controls the operation of the control means.

4. A valve including, a tubular mandrel adapted to be connected in a tubing string and having openings therein whereby communication between the well casing and mandrel is established, means for controlling the flow from the casing to the mandrel, a movable casing connected to

the control means for actuating the same and subjected to the well fluid within the well casing, the movable casing having a hollow portion at its upper end, said hollow portion having an open top 5 whereby the well fluid may enter the same, and resilient means capable of normally supporting the movable casing in its raised position, whereby when the casing is submerged in fluid the casing and control means is in one position and when 10 the fluid falls below the upper end of the movable casing the weight of the fluid trapped in the casing overcomes the tension of the resilient supporting means to move the casing and control means to its other position.

15 5. A valve including, a shell having an open lower end, a tubular mandrel extending axially within the shell and having openings therein whereby communication is established between the well casing and said mandrel, means for controlling the flow of fluid through said openings, a movable casing located between the mandrel and shell and connected to the control means and having a hollow portion at its upper end, said 20 hollow portion having an open top whereby well fluid from the well casing may enter the same, and means for supporting the movable casing to hold the control means open so long as the movable casing is submerged, the lowering of the fluid level below the top of said casing causing 25 fluid to be trapped in the casing and the weight of this fluid overcoming the supporting means to close the control means and cut off the flow, whereby the level of the fluid controls the operation of the control means.

30 6. A valve assembly including, a tubular mandrel adapted to be connected in a tubing string and having openings therein whereby communication between the well casing and interior of the mandrel is established, means for controlling the flow from the casing to the mandrel, a movable solid member connected to the control means exposed to the well fluids in the casing, and means for supporting the member to hold the control means open when the member is submerged in 35 the fluids, said means being overcome by the weight of the member when said member is not submerged, whereby the control means is closed 40 when the fluid level within the casing falls to a predetermined point.

7. A valve including, a tubular mandrel adapted to be connected in a tubing string and having openings therein whereby communication between the well casing and mandrel is established, means for controlling the flow from the casing to the mandrel, a movable casing connected to the control means for actuating the same and subjected to the well fluid within the well casing, the movable casing having a hollow portion extending downwardly from its upper end, said 10 hollow portion having an open top, whereby well fluid may enter the same, and a coiled spring, engaged beneath the movable casing capable of supporting said movable casing in its raised position, whereby the control means is held open 15 so long as the movable casing is submerged and when the fluid level falls below the upper end of the movable casing the weight of the fluid trapped in the casing overcomes the tension of the coiled spring to close the control means and 20 cut off the flow, whereby the level of the fluid controls the operation of the control means.

8. A valve including, a hollow body adapted to be connected in a tubing string and having openings therein for establishing communication between the well casing and tubing string, means for controlling the flow from the casing to the tubing string, and a non-buoyant movable means operatively connected with the hollow body for actuating the control means, said movable means 25 being unexposed to the pressure within the well tubing and being actuated by the fluid within the casing.

9. A valve including, a hollow body adapted to be connected in a tubing string and having openings therein for establishing communication between the well casing and tubing string, means for controlling the flow from the casing to the tubing string, a non-buoyant movable means operatively connected with the hollow body for 35 actuating the control means, said movable means being unexposed to the pressure within the well tubing and being actuated by the fluid within the casing, and a resilient means engaging the lower end of the non-buoyant means for aiding 40 in moving said means upwardly of the hollow body.

CHARLES S. CRICKMER.
HANS C. GLITSCH.
